UNITED STATES PATENT OFFICE.

PHILIP L. WOOSTER, OF YONKERS, NEW YORK, ASSIGNOR OF ONE-FOURTH TO
DURYEA MANUFACTURING COMPANY, A CORPORATION OF NEW JERSEY, AND
THREE-EIGHTHS TO BENJAMIN L. DURYEA, OF JERSEY CITY, NEW JERSEY.

PORTABLE CONVEYER.

1,031,501.

Specification of Letters Patent. Patented July 2, 1912.

Application filed September 16, 1908. Serial No. 453,257.

To all whom it may concern:

Be it known that I, PHILIP L. WOOSTER, a citizen of the United States, residing at Yonkers, in the State of New York, have invented certain new and useful Improvements in Portable Conveyers, of which the following is a specification.

This invention relates to that class of portable conveyers adapted to be used upon docks and wharves for the purpose of loading and unloading vessels, or for similar purposes, the device comprising a framework mounted upon wheels so that it can be pushed around and adapted when in use to rest at its opposite ends upon the two surfaces between which the freight is to be carried, the said framework supporting an endless conveyer belt and means for driving the same which is self-contained in the device, such as an electric motor.

The objects of the invention are to secure a simple construction the parts of which are not liable to get out of order; to provide ready access to the different parts of the device, and enable the motor to be removed if desired; to secure a strong construction which will not be racked or loosened by usage; to prevent any lodgment in the device of dirt or other droppings from the material being conveyed; to avoid a multiplicity of parts by making portions of the frame serve also as guideways for the conveyer belt; to secure a construction in which stock material can be largely used, and to obtain other advantages and results as may be brought out in the following description.

Referring to the accompanying drawings, in which like numerals of reference indicate the same parts in the several figures, Figure 1 is a side elevation of a portable conveyer of my improved construction in position for use; Fig. 2 is a side elevation, on larger scale, of that end of the conveyer where the conveyer belt can be adjusted; Fig. 3 is a plan of the conveyer; Fig. 4 is a section taken longitudinally of one of the conveyer belt slats and transversely of the supporting rail for said belt, as on line 4-4, Fig. 6, illustrating a certain friction shoe; Fig. 5 is a section transversely of the conveyer belt slat, as on line 5-5, Fig. 6; Fig. 6 is an underneath view of a portion of one of the slats provided with such friction shoes;

Fig. 7 is a transverse section of the conveyer taken on line 7-7, Fig. 8, looking in the direction indicated by the arrow; Fig. 8 is a side elevation of the middle portion of the conveyer, the adjacent wheel and a portion of the adjacent framework being broken away to show the construction more clearly; Fig. 9 is a vertical section of that end of the conveyer at which the conveyer belt is driven, said section being taken longitudinally of the conveyer, as upon line 9-9, Fig. 10; Fig. 10 shows in plan the opposite ends of the conveyer, the middle portion being broken away and the conveyer belt removed for greater clearness; Fig. 11 is a detail view looking at the ends of the conveyer belt slats, of another means for supporting the conveyer belt; Fig. 12 is a view of the same looking at the lateral edge of one of the conveyer slats, and Fig. 13 is an underneath view of portions of two slats connected by such supporting means.

In said drawings, the conveyer is shown as comprising a trussed frame which is as light as consistent with strength, and adapted to extend between the two points where freight or the like is to be carried. This frame consists of parallel upper bars 10, 10 of angle iron, which are preferably straight as shown, and beneath said upper bars 10, lower bars 11, 11 also of angle iron. These lower bars 11 are each inclined at their ends toward the upper bars 10 lying in the same vertical plane, while the middles are farther away from said upper bars, as shown in Fig. 1, so as to give a truss form to the frame. Beneath the said lower bars 11, 11 and parallel thereto, are other bars 12, 12 of T-iron, each arranged on edge with its stem portion projecting horizontally inward. Each of the said angle irons 10 and 11 is also arranged with one of its flanges projecting vertically upward and the other horizontally inward, as shown. Each upper bar 10 of the frame is connected with the lower bars 11 and 12 by means of transverse struts 13 and inclined braces 14 bolted to the outer sides of said bars, said struts and braces being preferably also of angle iron. If desired, these braces and struts 14 and 13 may be riveted to the longitudinal bars 10, 11 and 12, but preferably some of them, and especially those at the middle of the length of the con-

veyer, are removably bolted in place, so as to permit of their removal to obtain access to certain parts of the mechanism herein-after described. The two side portions of the frame are held in relative parallel positions by means of angle bars 15, secured beneath the upper bars 10 in the corners formed with the transverse struts 13, and by tubular separators or pieces of pipe 16 slipped upon tie-rods 17, Fig. 9 extending between the lower bars 11, 11, or 12, 12, and which tie-rods may also serve to rivet the upright struts and braces 13, 14 to the frame. At each end of the frame the T bars 12 extend somewhat beyond the lower angle bars 11 and are curved upwardly at their ends, as shown at 18 in Fig. 9, while the upper angle bars 10 are also shorter and straight at their ends like the lower ones 11. Plates 20 (or 21) are then laid flatwise against the outer sides of said ends of the bars and riveted, bolted, or otherwise secured thereto. Tie-rods 22 may also connect the two opposite end plates, with tubular separators thereon between said plates (see Fig. 9). A very strong and rigid frame is thus provided and beneath said frame at its middle is arranged an axle 23 with wheels 24 thereon which enable the conveyer to be conveniently moved from place to place. The said axle 23 is journaled in brackets 25, 25 suitably bolted or riveted to the bottom T bars 12 of the frame, as shown in Figs. 7 and 8.

Between the end plates 21, 21 at one end of the frame extends a transverse shaft 26, journaled at its ends in bearings 27 upon the said end plates. This shaft has fast upon itself a middle bevel gear 28 and sprocket wheels 29, 29 near its opposite ends. The end plates 20, 20 at the other end of the frame have slideways 30 formed therein and in which slideways are mounted boxes 31 adapted to be moved back and forth longitudinally of the frame by means of a screw 32 and nut 33 therefor, as is common. The said two boxes 31, 31 afford journal bearings for the ends of a transverse shaft 34, which shaft has near its ends sprocket-wheels 35, 35 in alinement with those 29, 29 just above described at the other end of the frame. These two sets of sprocket-wheels receive the endless conveyer belt 36 which will next be described. This conveyer belt comprises a series of transverse slats 37 each secured near its opposite ends to chains 38, 38, adapted to run upon and be driven by the said sprocket-wheels 29 and 35. These slats 37 lie at the upper part of the frame between the upwardly projecting flanges of the upper angle bars 10, 10, as shown in Fig. 7, and thus the belt is held positively against sidewise displacement. To support the said conveyer belt for the upper portion 65 of the frame, and the weight carried by said

belt, rails 39, 39 are arranged upon the angle bars 15, as shown in Figs. 7 and 10 more especially and upon which the transverse slats 37 slide. In order to prevent undue friction and wear of the slats 37 upon the said rails 39, I have shown in Figs. 4, 5, 6 and 7 the said slats each provided at the opposite edges of its under surface which engages a rail, with recesses 40, in which are run blocks 41 of Babbitt metal or the like to take the friction. These said recesses 40 have undercut walls and the block 41 has a stem projecting into a socket 42 of the slat, whereby the blocks or shoes 41 are securely retained in place. The said blocks or shoes project from the surface of the slat, as shown, so as to entirely relieve the latter of any friction. Furthermore, the said blocks or shoes can be replaced by new ones when desired, without great inconvenience. In returning, or at the lower part of the conveyer, the belt 36 passes idly between the horizontal flanges of the lower angle bars 11 and the stems of the T irons 12, the slats resting near their ends upon said stems and their ends abutting against the vertical portions of the T iron as shown in Fig. 7.

For driving the conveyer belt 36, an electric motor 42 is mounted inside the frame at its middle, being set on a platform 43 formed by plates 44 laid across between the lower angle bars 11, 11. This motor drives a pinion 45 which meshes with a gear 46 on a shaft 47 journaled transversely of the frame in bearings 48 upon two of the upright struts 13. This shaft also carries a bevel pinion 49 which meshes with a second bevel gear 50 upon a power-transmitting shaft 51 which extends longitudinally of the frame and is mounted in bearings 52 supported by angle-iron cross-bars 53 between the side struts 13. This shaft 51 has at its opposite end a bevel pinion 54 engaging with the bevel gear 38 on the sprocket shaft. Preferably the said shaft 51 is provided intermediate of its said ends with a clutch 56. Under some conditions, the said friction shoes 41 may be dispensed with, and the chain 57 which connects the slats and runs over the sprockets may be of a type having rollers 58 adapted to run upon the rails 39, all as shown in Figs. 11, 12 and 13. This chain is of any well known type, having sections 60 adapted to be secured to the slats 37, said sections being connected by pivoted pins 61, upon which the rollers 58 are mounted.

I have marked with reference numeral 19 the side strut which is shown removable to permit access to the motor 42 or to remove the said motor from the conveyer frame, and 55 indicates the bolts by which it is so removably secured. Obviously, more than one of the struts and braces could be so arranged, if desired.

Having thus described the invention what I claim is:

1. In a portable conveyer, the combination of an elongated frame having upper and lower horizontal pairs of parallel angle bars arranged each with one flange projecting vertically upward and the other horizontally inward, a pair of parallel T-bars beneath said lower angle bars having their ribs extending toward each other in horizontal planes, all the said bars at each side of the frame having their upright part in substantially the said vertical plane and the T-bars extending at their ends beyond the angle bars, end plates at each end of the conveyer secured to said T-bars and extending beyond the ends of the other bars, means for holding the bars spaced intermediate of said end plates, pairs of sprocket wheels one mounted at each end of the conveyer in said end plates and above the extended ends of the T-bars, an endless conveyer belt extending around said sprocket wheels with its portion above said wheels lying above the horizontal flanges of the upper angle bars and between the vertical flanges thereof and its lower portion below said sprocket wheels lying beneath the horizontal flanges of the lower angle bars and upon the inwardly projecting ribs of the
2. In a portable conveyer, the combination of an elongated frame comprising upper and lower horizontal pairs of parallel angle bars, the bars of each pair being arranged with one flange projecting upward and the other inward, a pair of parallel T-bars beneath said lower angle bars, said T-bars being longer than the other bars and having their extremities curved upward, rails arranged horizontally and longitudinally between the angle bars of the upper pair and having their extremities extending beyond the said angle bars and curved downward, end plates secured to the said upturned extremities of the T-bars at the sides of the frame and overlapping the ends of said T-bars and angle bars and rails, sprocket wheels between said end plates, an endless conveyer belt upon said sprocket wheels adapted to return idly upon the ribs of said T-rails and to travel forward upon the said rails, and means for driving said conveyer.

PHILIP L. WOOSTER.

In the presence of—

B. L. DURYEA,
RUSSELL M. EVERETT.
